Primary Examiner — Justin M Jonaitis*Assistant Examiner* — Natalya M Rapundalo(74) *Attorney, Agent, or Firm* — McDonald Hopkins LLC(57) **CLAIM**

The ornamental design for a storage and serving assembly for food product as shown and described.

DESCRIPTION

FIG. 1 is a front perspective view of a storage and serving assembly for food product;

FIG. 2 is a front side view of FIG. 1 thereof;

FIG. 3 is a rear side view of FIG. 1 thereof;

FIG. 4 is a right side view of FIG. 1 thereof;

FIG. 5 is a left side view of FIG. 1 thereof;

FIG. 6 is a top plan view of FIG. 1 thereof;

FIG. 7 is a bottom plan view of FIG. 1 thereof; and,

FIG. 8 is a rear perspective view of FIG. 1 thereof.

The broken lines show portions of the storage and serving assembly for food product and form no part of the claimed design.

1 Claim, 6 Drawing Sheets(56)
